F. PALMÈS.
SWIMMING APPLIANCE.
APPLICATION FILED MAR. 29, 1919.
1,316,639.

Patented Sept. 23, 1919.

UNITED STATES PATENT OFFICE.

FERMIN PALMÉS, OF EDDYSTONE, PENNSYLVANIA.

SWIMMING APPLIANCE.

1,316,639.

Specification of Letters Patent. Patented Sept. 23, 1919.

Application filed March 29, 1919. Serial No. 286,119.

To all whom it may concern:

Be it known that I, FERMIN PALMÉS, a subject of the King of Spain, residing at Eddystone, county of Delaware, State of Pennsylvania, have invented a new and useful Swimming Appliance, of which the following is a specification.

My invention consists of a novel construction of an appliance adapted to be attached 10 to the foot of a bather or swimmer to facilitate his progress through the water in the act of swimming and comprises a suitable body portion adapted to be secured to the swimmer's foot and having hinged side 15 wings or blades which are adapted to swing toward each other when the swimmer brings his knees and feet toward his body and which are adapted to automatically move outwardly and extend in the same plane 20 when the swimmer moves his knees and feet away from his body in the act of propelling himself forwardly whereby the swimmer is enabled to propel himself forwardly through the water more rapidly and with less fatigue 25 than heretofore.

To the above ends my invention consists of a novel construction of appliances for swimmers adapted to be strapped or otherwise secured to the foot of the swimmer and 30 comprising a suitable body portion and hinged spring actuated wings or blades carried thereby for the purpose stated.

For the purpose of illustrating my invention, I have shown in the accompanying 35 drawing one form thereof which is at present preferred by me, since the same will be found in practice to give satisfactory and reliable results, although it is to be understood that the various instrumentalities of 40 which my invention consists can be variously arranged and organized and that my invention is not limited to the precise arrangement and organization of these instrumentalities as herein shown and described.

45 Figure 1 represents a side elevation of a swimming appliance embodying my invention, showing the same as applied to the foot of the user.

50 Fig. 2 represents a bottom plan view of Fig. 1.

55 Fig. 3 represents a section on line 3—3 of Fig. 2.

Similar numerals of reference indicate corresponding parts.

55 Referring to the drawings.

1 designates my novel construction of an

appliance for facilitating swimming, the same comprising a suitable central plate or body 2 having the straps or fastening devices 3 attached to the forward portion 60 thereof, the same being adapted to fit or be strapped over the wearer's instep. 4 designates a suitable pocket or receptacle for the heel and ankle of the wearer, which is preferably formed by a strip of suitable material 65 having its lower edge secured to the left-hand or curved end of the body 2 by the fastenings 5, said receptacle 4 being provided with a flap 6 which fits snugly over the ankle of the wearer and is provided 70 with fastening devices such as straps, buckles or the like 7, so that both ends of the body 2 can be secured in position upon the wearer's foot, as seen in Fig. 1. The body or base member 2 on its under side is provided 75 at each edge with the longitudinally extending angular recesses 8, in which the longitudinally extending plates, blades or wings 9 are secured by means of the hinges 10 or the like, there being preferably two pairs of 80 said hinges 10 as will be understood from Fig. 2. The hinge members or leaves comprising the hinges 10 have knuckles which are pivotally secured together by pins which have the ends or arms 11 extending at a 85 right angle or transversely to or upon the body 2, while their opposite ends 12 extend parallel to said body and along the wings 9. As will be understood from Fig. 2, the function of said ends 11 and 12 is to exert a slight 90 torsional action on the wings 9, so as to cause them to normally appear as seen in Fig. 2 and in full lines in Fig. 3.

The position the parts assume when the 95 appliance is strapped to the foot of the wearer will be understood from Fig. 1. The position that the blades or wings 9 assume when the wearer is moving his knees or feet toward his body in the act of swimming will be understood from the dotted lines seen in 100 Fig. 3.

When the swimmer is moving his knees or feet away from his body in the act of swimming so as to propel himself forwardly, it will be understood that the plates or blades 105 9 assume the position seen in full lines in Fig. 3, the walls of the longitudinally extending recesses 8 serving as abutments to hold said wings in the position seen in full lines in Figs. 2 and 3. It will be apparent 110 that by my novel appliances, a swimmer can propel himself rapidly through the water

without undue fatigue and that the hinged wings when in position upon the swimmer's feet automatically assume the proper position.

5 It will now be apparent that I have devised a novel and useful construction of a swimming appliance which embodies the features of advantage enumerated as desirable in the statement of the invention and
10 15 the above description and while I have, in the present instance, shown and described a preferred embodiment thereof which will be found in practice to give satisfactory and reliable results, it is to be understood that the same is susceptible of modification in various particulars without departing from the spirit or scope of the invention or sacrificing any of its advantages.

Having thus described my invention, what
20 I claim as new and desire to secure by Letters Patent, is:—

A device of the character described, comprising a central body portion formed in one piece and provided upon its lower side with
25 longitudinal recesses, securing elements arranged above the central body and attached thereto and adapted to receive portions of the foot, wings having their inner edges adapted to enter the recesses when in the

open position and to engage the walls of the 30 recesses, said wings and the lower portion of the central body being arranged in substantially the same plane, and three part leaf hinges serving to connect the wings and central body, each leaf hinge embodying an 35 inner leaf arranged beneath the central body and extending transversely of the lower portion thereof throughout its entire width and attached thereto and provided at its ends with knuckles, outer leaves arranged beneath 40 the wings and secured thereto and provided at their inner ends with knuckles to coact with the knuckles of the inner leaf, and pins extending through the sets of knuckles for pivotally connecting them, each pin having 45 its ends extending outwardly beyond the knuckles, one end engaging the central body and the opposite end being bent upon itself to extend approximately longitudinally of the corresponding wing and to engage with 50 the adjacent outer leaf, the last named end being capable of being bent laterally for adjusting the tension exerted by the pin.

FERMIN PALMÉS.
